CHIN CORRECTIVE DEVICE

Agnes G. McCarthy, Buffalo, N. Y.

Application July 30, 1953, Serial No. 371,204

4 Claims. (Cl. 128—76)

1

This invention relates to a cosmetic or chin contour corrective device which serves as a beauty aid by reducing or eliminating the appearance of fleshiness below the chin of the user.

Prior art devices, sometimes called chin straps, are provided for bedtime use in attempts to reduce or control the fleshy tendency known as a double chin. The corrective effect of these devices is problematical. However, the present invention provides a device which primarily reduces or eliminates the appearance of under-chin fleshiness while it is being used and is of such nature that it may be worn publicly without disclosing its nature and purpose and with the appearance of being merely a piece of jewelry or ornamentation.

Generally speaking, the device of the present invention looks like a necklace when it is in use and, in fact, may comprise an attachment to existing necklaces, although the primary form illustrated herein is a necklace specially designed to accomplish its dual purpose as a beauty aid or cosmetic device and as an article of ornamentation.

The device of the present invention exerts a rearward pull at the surface of the flesh at two points at the side of the neck of the user, these points lying generally in vertical alignment with the ears and at points slightly below the jaw line. It is found that such a pull, which is of course actually very slight, draws back the skin to substantially reduce or practically eliminate the appearance of fleshiness beneath the chin without discomfort to the user and without any indication of the true corrective nature of the device. This fleshy appearance is really most often a muscular sagging or slackness.

A fuller understanding of the principles of the present invention will be had from a consideration of the accompanying drawing and the following detailed description of an exemplary form of the device of the present invention. However, it is to be understood that the principles of the invention are of general application and may be varied somewhat, as will appear from the following discussion. The principles of the present invention are not limited to the device set forth herein by way of example but only as defined in the appended claims.

In the drawings:

Fig. 1 is a general side elevational view of a portion of the head and neck of a user of the device of the present invention with one form of the latter in a normal position of use;

2

Fig. 2 is a general top plan view of the form of the present invention illustrated in Fig. 1; and

Fig. 3 is an enlarged detailed cross-sectional view through one of the flesh engaging members of the device of Figs. 1 and 2.

In the drawing like characters of reference denote like parts and the numerals 10 and 11 designate, respectively, the head and neck of a user of the form of the device of the present invention illustrated and described in detail hereinabove by way of example. An under-chin fleshiness of the general type which the device of the present invention is intended to correct, reduce, or eliminate is indicated in dot and dash lines in Fig. 1 at 12.

Essentially, the device of the present invention, in the form set forth in the accompanying drawing, comprises a pair of flesh or skin engaging members adapted to be secured at the opposite sides of the neck of the wearer, with a resiliently extensible or tension-exerting band extending around the back of the neck to connect between the two flesh or skin engaging devices.

The flesh or skin engaging members are designated generally 14 and 15, Figs. 1 and 2 and one of them is shown cross-sectionally on an enlarged scale and in detail in Fig. 3. The form of the flesh or skin engaging members may vary very widely in practice and the form set forth herein is merely by way of example.

Referring to Fig. 3, the flesh or skin engaging device 15 there shown in detail comprises a disk 16 of metal, plastic, or other suitable material which in the illustrated instance has flanged outer edges to provide a raised central portion. A disk of adhesive material or of thin relatively flexible material coated at both of its opposite sides with adhesive is, in the form illustrated by way of example, adhesively secured to the central raised portion of disk 16 as at 17 in Fig. 3.

Since both surfaces of the element 17 are adhesively coated or of an adhesive nature, the outer surface thereof is adapted to be pressed against the skin at the proper point on the neck of the user and thus temporarily attached thereto. The adhesive disks 17 may be of a readily disposable nature so that a user may apply new adhesive disks 17 to the metal or plastic disk 16 each time the device is worn or as often as is necessary to maintain a desired adhesiveness.

Disk 16 is provided with an eye 18 or a similar attaching device for one end of a band 19, the latter being provided centrally with a detachable connector or fastener 20 as shown in Fig. 2.

Band 19 may be of the spring-extensible type familiarly used as wrist watch bracelets or of any similar form adapted to exert a tensile pull upon the opposite flesh engaging members 14 and 15, when the device is in use. Also, the connector 5 or fastener 20 may be of the usual type found in necklaces, watch bracelets or similar articles of ornamentation.

By experience, the user will know approximately the points at which the disks 14 and 15 are to be adhesively applied to the side of the neck, these points being such that when the extensible band 19 is secured as by means of the fastener 20, the band will exert a rearward pull on each of the flesh engaging members 14 and 15 and thus draw the under-chin skin and flesh rearwardly to approximately the full-line position illustrated in Fig. 1. The device, thus applied and used, is found to improve the chin line of a wearer to a remarkable degree when the wearer is prone to under-chin fleshiness, as described hereinbefore.

At their forward portions the flesh engaging members 14 and 15 are provided with means for attaching to a necklace band 22 of any desired ornamental nature so that when in use, and without any attempt at concealment of any part of the device, the entire device appears to be merely an ornamental necklace. In Fig. 1 the dot and dash lines 25 indicate the manner in which a wearer's hair may conceal portions of the device but such concealment is, by the very nature of the device of the present invention, not at all essential.

Band 19 may be provided with any desired form of length adjustment to fit the user and to allow for the proper degree of rearward pull on the flesh engaging members 14 and 15. If desired the lengthwise adjustment may be incorporated in the fastener 20. The device of the present invention is illustrated herein as comprising a complete necklace but in one commercial form it may comprise merely the members 14 and 15 and the rearward band 19, with means on the members 14 and 15 for attaching a variety of frontal ornaments to suit various personal tastes or various costume schemes.

As a further alternative the flesh engaging members 14 and 15 may be arranged for ready attachment to opposite side portions of existing necklaces, in which case the rear portion of a necklace proper would serve as the rearward tensioning element. As described herein, it is preferred to employ resilient means for applying rearward tension to the members 14 and 15, 55 but a non-extensible band would serve a similar

purpose. In the latter case, however, the length adjustment of the rear band portion would necessarily be much more precise in order to apply the desired degree of rearward tension to the members 14 and 15.

What is claimed is:

1. A necklace-simulating cosmetic device adapted to be applied to the neck of a user and comprising a pair of spaced flesh engaging elements including means for adhesively securing the same to opposite sides of the neck, a resilient flexible tension member connecting said elements and adapted to extend about the back of the user's neck, and an ornamental band connected at its opposite ends to said elements and adapted to extend forwardly to cooperate with said tension member to simulate a necklace.

2. A necklace-simulating chin contour corrective device comprising a pair of spaced flesh engaging elements including means for securing the same to the skin at opposite sides of the neck, a resilient flexible tension member connecting said elements and adapted to extend about the back of the user's neck, and an ornamental band connected at its opposite ends to said elements and adapted to extend forwardly to cooperate with said tension member to simulate a necklace.

3. In combination with a necklace device including a resiliently extensible rear portion, a pair of skin engaging elements attached to said necklace at opposite lateral points and including means for adhesively securing said elements to opposite sides of the neck whereby the rear resilient extensible portion of said necklace draws the skin engaging elements rearwardly and exerts a rearward pull on the under-chin surface flesh of the user.

4. In combination with a necklace device including a resiliently extensible rear portion, a pair of attaching elements carried by said necklace at opposite lateral points and including means for securing said elements to the skin at opposite sides of the neck whereby the rear resilient extensible portion of said necklace draws the attaching elements rearwardly and thus exerts a rearward pull on the under-chin surface flesh of the user.
